UNITED STATES PATENT OFFICE.

HENRY SMITH, OF NEW YORK, N. Y.

AUTOMATIC CUT-OFF FOR GAS-BURNERS.

SPECIFICATION forming part of Letters Patent No. 779,006, dated January 3, 1905.

Application filed March 24, 1904. Serial No. 199,672.

To all whom it may concern:

Be it known that I, HENRY SMITH, a citizen of the United States, and a resident of New York, in the county of New York and State 5 of New York, have invented certain new and useful Improvements in Automatic Cut-Offs for Gas-Burners, of which the following is a specification.

The subject of the present invention is a 10 novel automatic cut-off for gas-burners, and has more particularly in view simple and efficient means of the character stated capable of being applied to existing constructions of fixtures with comparatively little labor and 15 expense and which will absolutely insure the flow of gas to the burner so long as the flame exists at the tip thereof, but which will positively cut off the supply of gas to said burner when the flame of the latter becomes extinguished through causes other than the result 20 of the closing of the gas-cock.

A development of the invention comprises generally a receptacle containing mercury and preferably of glass, which receptacle is adapted 25 to be so mounted on a burner that while not liable to injury by the flame its mercury contents will be sensible to the heat radiated from the burner, so that the mercury will expand to close a circuit energizing an electromagnet, 30 the energizing of such magnet serving to exert a slight pull on an armature which has previously been brought within the range of the magnetic field and retained therein by a normally retracted keeper. The armature is 35 connected with the key of the gas-cock, and the latter is so conditioned that it will ordinarily be closed with the armature out of position. Upon moving the armature to bring it within the range of the magnetic field aforesaid the 40 cock will be opened to supply gas to the burner, and by then moving the keeper to engage said armature both the latter will be held against their retracting tendencies, whereby the cock will thus be maintained open. The energization 45 of the magnet above referred to will initially move said armature out of engagement with the keeper, so that the latter will be retracted out of the way, the armature, however, continuing in the position corresponding 50 with the open condition of the cock by reason

of the maintenance of the closed circuit induced by heat generated by the flame at the burner, the gas issuing from which having in the meantime been ignited. Should the flame become unintentionally extinguished, the consequent contraction of the mercury will interrupt the circuit, deenergize the magnet, and permit the normal retracting agency of the armature to move the same, so as to effect an automatic cut-off of the gas-supply to the 60 burner.

There are other important features connected with my invention, which, besides those alluded to, are clearly explained in the subsequent detailed description.

In the accompanying drawings, forming part of this specification, Figure 1 is a side view of a gas bracket or fixture equipped with one form of my invention, the parts being represented in the position they occupy immediately 70 upon lighting the gas. Fig. 2 is a detail view showing in inverted plan and on a somewhat larger scale the cock portion of the fixture and parts contiguous thereto as exemplified in the preceding figure. Fig. 3 is a detail sectional view of the fixture equipped with the novel cut-off means, the section being in the plane indicated by the broken line 3 3, Fig. 1, but the parts being represented on a larger scale and dotted lines illustrating the 80 position of the armature when the cock is closed. Fig. 4 is a detail view illustrating an arrangement whereby the keeper is adapted to be automatically retracted and held out of position by gravity.

Similar reference characters are employed to designate corresponding parts in the several figures of the drawings.

Considering now Figs. 1 to 3, inclusive, A refers to a gas-cock, which may be of the ordinary key-operated ported-plug type and which is interposed in the fixture or bracket at some point between the burner B and the primary cock C, which latter is similar in construction and operation to the cock A. 90 For convenience the cocks A and C will be contiguously located. A torsional spring *a* embraces the adjacent portions of the casing of the cock A and the key A' thereof, one end of said spring being connected with said casing, 95 100

while the other end of this spring engages the key, such spring a being so conditioned that it tends to normally hold the cock in the closed position. Secured to one side of the key by 5 screws d or in any suitable manner is a vertically flat member D , preferably of brass, which extends horizontally and has attached at the opposite end thereof the overlapping portion of a correspondingly-disposed armature D' .

In a plane coincident with that of the key A' is a pair of transversely-arranged electromagnets E E , the latter being supported by a rigid connection E' with the fixture, the connection illustrated comprising a curved arm 15 secured at one end to the core-bridge e at the rear of the magnets, while the other end carries a divided sleeve e' , adapted to firmly clamp the fixture by means of a binding-screw e'' . As indicated by dotted circles in 20 Fig. 1, the magnet-poles e^3 e^3 are so positioned that the armature D' can be moved to bring it within the range of the magnetic field of the magnets E .

On that side of the casing of the cock A corresponding with the side of the key A' at which the member D is located is attached a plate F , one manner of attaching which is shown as consisting of a stud f , tapped into and projecting from the casing side through the plate and having its outer extremity riveted against said plate. To further insure the proper retention of this plate in position, it has an ear f' , bent to intimately occupy a depression in 30 the fixture, the securement being further augmented, if necessary, by soldering the ear within the depression. The plate F likewise has an integral horizontal shank F' , to the outer end of which is pivotally attached a 35 vertically-movable keeper G , desirably of the angular configuration indicated, one member, g , being that pivotally connected to the shank F' , while the other member, g' , is curved, so that when the keeper is turned to the position indicated in Fig. 1 the extremity of the 40 last-mentioned member will frictionally engage the back of the armature D when the same is in apposition to the magnet-poles and hold the armature in such position. A torsional spring g^2 embraces the shank F' of the 45 plate F and has a portion g^3 engaging the keeper G , so as to normally hold the latter out of the plane in which the armature moves.

Attached to the burner-pedestal by any suitable means—as, for instance, a screw-contracted clip h —is a thermostatic circuit-closer in the form of a receptacle, preferably of glass and shown as comprising a bulb H , located to be sensible of heat radiated from the 55 upper part of said burner-pedestal, a vertical tubular leg h' of restricted diameter communicating with and depending from said bulb at the bottom of the latter, said leg merging in a lower bend, from which continues an extended upwardly-inclining tubu-

lar leg h^2 , corresponding in diameter with the leg h' , the leg h^2 terminating at its upper end in a bulb h^3 , considerably smaller than the bulb H . A small short leading-in section i of platinum is fused in and extends through 70 the glass of the bulb H , so as to be in contact with a body of mercury therein. A similar section i' of platinum is correspondingly located in the upper end portion of the leg h^2 , so that one extremity of said section i' extends with the interior of said leg. One of the sections, i' , is connected by wire i'' through battery I to the coil-terminal of one of the electromagnets E , while the other section, i , is connected by wire i^3 to the coil-terminal of 80 the electromagnet E , thus forming a circuit incomplete at an intermediate point h^4 within the leg h^2 of the thermostatic circuit-closer.

From the description thus far it will be readily comprehended that when the gas is to 85 be ignited the armature D' is moved to bring it into apposition with the magnet-poles and simultaneously open the cock A . While the armature is so held the keeper G is adjusted so that its rounded extremity will contact 90 with the back of the armature, with the result that both the latter and the keeper will be frictionally retained in the positions stated. The cock C can then be opened and the gas ignited at the burner-tip. As soon as the 95 burner-pedestal becomes sufficiently warm to expand the mercury to such extent that it will bring the gap at h^4 in the leg h^2 the electric circuit will be completed, thereby energizing the magnets E E , so that the armature will 100 be attracted and held by the same, the slight pull thus induced destroying the frictional contact between said armature and keeper and permitting the spring g^2 to retract said keeper out of position. Obviously the armature will 105 be thus maintained with the cock A open as long as the flame is present; but should said flame be extinguished the resulting contraction of the mercury will again interrupt the 110 circuit and the armature be released, so that the torsional spring a will turn the key A' to close its cock and cut off the flow of gas to the burner. The thermostatic tube is adjusted at such distance from the locale of the gas-flame that after the maximum absorption of 115 heat by the mercury the latter will not rise in the leg h^2 far beyond the point of contact with the platinum section i' therein. Moreover, the mercury would not drop sufficiently 120 to break the circuit when the flame is turned low. By this means adjustment to meet different flame conditions can be nicely provided for.

Instead of retracting the keeper by a torsional spring the said keeper can be correspondingly operated by gravity. Fig. 4 illustrates one arrangement for accomplishing this result. In said figure the pivotal portion g^4 of the keeper G' is prolonged beyond the pivotal point and weighted, as indicated at g^5 , to 130

throw the engaging end of said keeper out of position when released from frictional contact with the armature.

In constructions where the turning-key occupies an inverted position—or, in other words, one the reverse to that illustrated—the electromagnets can be arranged in a coincident horizontal plane, and the keeper can then be conditioned to drop by its own weight when released. It will also be manifest that the frictional engagement of the keeper with the armature is of such delicate character that magnets of low electromotive force can be utilized, thus admitting of the employment 15 of a single battery-cell of exceedingly small current force.

The automatic cut-off can, when desired, be rendered inoperative by the inclusion at a suitable point in the circuit of a hand-operated 20 circuit-opening device I'.

In the event of the improvements being employed in connection with a Welsbach burner the thermostatic circuit-closer can be supported by an arm or bracket on the fixture beneath such burner and supporting the mercury-receptacle, so that the leg h' thereof and its bulb H will be within the chimney, contiguous to the base of the burner proper.

I do not desire to be understood as limiting 30 myself to the precise arrangement and construction of parts shown and described, but reserve the right to all modifications within the scope of my invention.

Having now described my invention, what 35 I claim as new, and desire to secure by Letters Patent, is—

1. In an automatic cut-off for gas-burners, the combination with a burner and a self-closing cock, of an armature movable with said 40 cock, an electromagnet and a normally retracted keeper each adapted independently of the other to hold the armature with the cock in an open position, electric-circuit provision including the magnet-coils, and a thermostatic

circuit-closer interposed in said circuit and 45 designed for attachment to the burner for location below the plane of the flame zone whereby said circuit-closer will be sensible more especially to heat radiated from the body of the burner.

2. In an automatic cut-off for gas-burners, the combination with a burner and a self-closing cock, of an armature movable with said cock, an electromagnet and a normally retracted keeper each adapted independently of 50 the other to hold the armature with the cock in an open position, electric-circuit provision including the magnet-coils, and a mercury circuit-closer interposed in said circuit and 55 designed for attachment to the burner for location below the plane of the flame zone whereby said circuit-closer will be sensible more especially to heat radiated from the body of the burner.

3. In an automatic cut-off for gas-burners, 60 the combination with a burner and a normally spring-closed cock, of an armature movable with the key of said cock, a normally retracted pivoted keeper for engaging the armature to hold the cock in an open position, an electromagnet, suitable electric-circuit provision connected with the magnet-coils, and a thermostatic circuit-closer interposed in said circuit and in the form of an attachment externally 65 clamped on the burner below the plane of the 70 flame zone, said circuit-closer adapted to be operated to close the circuit to energize the magnet to release the armature from the keeper, and thereafter hold said armature to maintain the open position of the cock.

Signed at New York, in the county of New York and State of New York, this 10th day of March, A. D. 1904.

HENRY SMITH.
